COMBINED JUG AND CONTAINER

Filed May 15, 1940

FIG. 1

FIG. 2

Herman L. Brooks

INVENTOR.

UNITED STATES PATENT OFFICE

126,427

DESIGN FOR A COMBINED JUG AND CONTAINER

Herman L. Brooks, New York, N. Y., assignor to
Coty, Inc., Wilmington, Del., a corporation of
Delaware

Application May 15, 1940, Serial No. 92,387

Term of patent 3½ years

To all whom it may concern:

Be it known that I, Herman L. Brooks, a citizen of the United States, residing in the city and State of New York, have invented a new, original, and ornamental Design for a Combined Jug and Container, of which the following is a specification, reference being had to the accompanying drawing, forming a part thereof.

In the drawing:

Figure 1 is a side elevational view of a combined jug and container, showing my new design.

Figure 2 is a top plan view thereof, with the upper portion of the container being removed.

I claim:

The ornamental design for a combined jug and container, substantially as shown.

HERMAN L. BROOKS.
